UNITED STATES PATENT OFFICE.

GRANT SIPP, OF PATERSON, NEW JERSEY.

WINDING MACHINE.

Application filed August 19, 1926. Serial No. 130,204.

This invention relates to that class of winding machines in which the package being wound rotates on a horizontal axis, being revolubly arranged in spaced bearing brackets and having a whirl or equivalent which rests on a driving wheel and is thereby rotated, the brackets being formed so as to afford bearings for the journals for the package adapted to hold the latter with its whirl resting on the wheel but capable of up and down motion, at least at the end thereof having the whirl. Generally a number of the brackets, supporting packages to be wound all at once, are arranged in a row and usually each bracket has one side formed with an upwardly open notch and the other with a slot, so that each bracket functions as a rest and as a guide for the adjoining journals for two adjoining packages.

It has heretofore been impossible to support the packages in the machine so that they would be accurately spaced and otherwise accurately positioned, with the consequence that the machine did not operate at full efficiency and the winding was more or less faulty. Moreover, when the bearings became worn by the package journals there was no other alternative than to continue the brackets in use, with consequent faulty winding, or to replace the brackets with new ones. The object of this invention is to provide a bracket which will permit accurate initial setting of the packages and insure their running with as little looseness in their bearings as possible and also permit adjustment to be effected when necessary, due to wear or other causes, without disturbing the bracket as a whole. This I accomplish by forming each bracket as to its major portion substantially as heretofore but so that the actual bearing-including portion thereof is a separate element which is capable of adjustment in the major portion and if need be removable therefrom.

In the drawing,

Fig. 1 is a front elevation of one winding unit of a winding machine embodying the invention;

Fig. 2 is a side elevation thereof, with certain parts in section on line 2—2, Fig. 1;

Fig. 3 is a plan of one bracket and a part of the frame;

Fig. 4 is a fragmentary side elevation of said bracket;

Fig. 5 shows the said bearing-including portion in longitudinal section; and

Fig. 6 shows a modification thereof.

1 designates two horizontal bars forming a part of the machine frame, and 2 the clips by which, together with a screw 3, each bracket is secured to these bars by clamping in the usual way.

What I term the body member of each bracket includes a base 4 (which receives said screw and coacts with the clip 2 in the mentioned clamping) and an integral arm 5 projecting from the upper portion of the base. The end of this arm has a horizontally arranged transverse opening 6 (here cylindrical) penetrating it and it is also split, as at 7, in a horizontal plane bisecting the hole 6 and from the terminus of the arm rearwardly, or toward the base. The split portion of the arm has a vertical hole 8 which is screw-threaded at 8^a, Fig. 4, below the split but smooth above it and preferably formed with a counterbore 8^b at its upper end; this hole receives a cap-screw 9 which is tapped into its screw-threaded portion and bears with its head against the bottom of the counterbore. Back of the opening 6 the arm is formed at one side with a lateral rest 10, with a concave seat 10^a, and this rest is developed upwardly to form an abutment 11.

The bearing member is a block or piece 12, here formed cylindrical and of a diameter to be received by hole 6 and a length somewhat greater than the width of the arm. In one end thereof a bearing is formed by a socket or bore 12^a and in the other end is formed a bearing existing as a transverse slot 12^b of the same width as the socket or bore 12^a. It is secured in the hole 6 by the cap-screw.

The package as a whole is designated 13, and may include with the windings of yarn the spool 13^a and the spindle 13^b carrying the spool in the usual way and having the whirl 13^c, the ends of the spindle affording the mentioned journals for the package. 14 is one of the driving wheels of the machine suitably driven and arranged to rotate on a horizontal axis below the row of brackets (two of which appear in Fig. 1) so as to rotate the corresponding package when the same has been mounted in its pair of brackets and the whirl 13^c therefor bears on the wheel as shown in said figure.

- In setting up the machine the brackets are first positioned so as to bring their body members as near as possible in proper spaced relation to each other and properly alined.
- 5 Thereupon their several bearing members are adjusted lengthwise in their holes 6 to obtain accurate spacing thereof with respect to the packages and also rotatively, being finally secured fast by the cap-screws.
- 10 The bearings 12^a and 12^b of the bearing members of two adjoining brackets may then receive the opposite ends of the spindle, as shown in Fig. 1.
- Thus in setting up the machine, however inaccurately the brackets may be spaced it is possible to space their bearing portions to a nicely; it is also possible to set said bearing portions so that the slots are more or less inclined, thus to restrain the up and down motion of the package and avoid consequent loss of traction. After the machine is in use if wear occurs permitting undue lengthwise movement of the packages it may be taken up without disturbing the 25 brackets, or any of them, as a whole; or if a package journal wears a depression in the side of the corresponding slot, so that traction between the package and wheel is lost, the bearing member may be rotatively 30 adjusted to shift the point of contact therewith at said side of the slot, or to the extent of 180° if necessary to afford an entirely new bearing at the other side of the slot, or it may be replaced by a new bearing member, the bracket body member in all cases 35 remaining undisturbed.

In Fig. 6 a form of bearing member is shown which is adapted for a package having a whirl on each end so as to be driven by two driving wheels with one whiri on each wheel. In this form the bearing member 15 has a slot 15^a in each end thereof forming its bearing.

Having thus fully described my invention, what I claim and desire to secure by Letters Patent is:

1. The combination, with a winding machine frame and a driving wheel rotatable therein on a horizontal axis, of means to support the package to be rotated in peripheral contact with the wheel and with its axis substantially horizontal including a bracket body member projecting from the frame and a bearing member removably secured in the body member and having a slot bearing extending across said bearing member transversely of the package axis and receiving a journal of the package.

2. The combination, with a winding machine frame and a driving wheel rotatable 60 therein on a horizontal axis, of means to support the package to be rotated in peripheral contact with the wheel and with its axis substantially horizontal including a bracket body member projecting from the frame and a bearing member removably secured in the body member and having a slot bearing extending through said bearing member transversely of the package axis and receiving a journal of the package, said bearing member being adapted to be received by and removably secured in the body member with its slot bearing reversed end for end.

3. The combination, with a winding machine frame and a driving wheel rotatable 75 therein on a horizontal axis, of means to support the package to be rotated in peripheral contact with the wheel and with its axis substantially horizontal including a bracket body member projecting from the frame and a bearing member adjustable in the body member lengthwise of the package axis and having a slot bearing extending across said bearing member transversely of the package axis and receiving a journal of the package.

4. The combination, with a winding machine frame and a driving wheel rotatable 90 therein on a horizontal axis, of means to support the package to be rotated in peripheral contact with the wheel and with its axis substantially horizontal including a bracket body member projecting from the frame and a bearing member adjustable in the 95 body member around the package axis and having a slot bearing extending across said bearing member transversely of the package axis and receiving a journal of the package.

5. The combination, with a winding machine frame and a driving wheel rotatable 100 therein on a horizontal axis, of means to support the package to be rotated in peripheral contact with the wheel and with its axis substantially horizontal including a bracket 105 body member projecting from the frame and a bearing member adjustable in the body member around the package axis through substantially 180° and having a slot bearing extending through said bearing member transversely of the package axis and receiving a journal of the package.

In testimony whereof I affix my signature.

GRANT SIPP.
